Fig. 3

Fig. 4

Fig. 6

Fig. 7

Fig. 8

FIG. 1 is a perspective view of a cabinet for water distillation apparatus showing my new design;

FIG. 2 is a front elevation thereof;

FIG. 3 is a rear elevation thereof;

FIG. 4 is a side elevation thereof;

FIG. 5 is a perspective view of a further embodiment of the cabinet disclosed in FIG. 1;

FIG. 6 is a front elevational thereof;

FIG. 7 is a rear elevation thereof;

FIG. 8 is a side elevation thereof;

In each cabinet, the side not shown is substantially a mirror image of the side shown.

I claim:

The ornamental design for a cabinet for water distillation apparatus, substantially as shown and described.
